OIL BURNER

Harry F. Tapp, Longmeadow, and Leolyn F. Spear, Westfield, Mass., assignors to Gilbert & Barker Manufacturing Company, West Springfield, Mass., a corporation of Massachusetts

Application January 27, 1940, Serial No. 315,940

10 Claims. (Cl. 158—36)

This invention relates to improvements in oil burners and, more particularly, to improvements which enable satisfactory operation with the use of relatively heavy and viscous fuel oils.

The invention has for its general object the provision in an oil burner of means for preheating the oil and for bringing all oil within the burner structure up to a selected predetermined temperature in as short a time as possible and before flow of any oil from the nozzle is permitted.

The invention has for a particular object the provision of two oil-heating means, one of which is associated with the boiler, or other heating unit, and dependent for its effectiveness on operation of that unit and the other of which is operable independently of the unit and can be brought into effective operation coincidentally with the starting up of the motor-driven pump of the burner, together with a means for initially circulating a relatively small body of oil in a relatively short path which includes the second and excludes the first heating means. The oil thus circulated heats the necessary parts of the burner structure, particularly the oil supply passages to the nozzle and the nozzle itself, and a quick raising of the temperature can be effected. After the initial heating of the oil in this manner, oil is permitted to flow to the nozzle for ignition and the oil used for heating purposes is caused to circulate in a longer path which includes the first heating means.

The invention also has for an object to provide in a burner of the type described, a valve which is responsive to oil temperature and which controls the flow of oil into the feed conduit of the oil-atomizing nozzle and opens only when such oil has been raised to the desired predetermined temperature, together with a circulatory oil-heating system including jackets or other passages which extend along opposite sides of said conduit from end to end thereof, whereby all the oil that is trapped between the valve and nozzle may be effectively heated.

Another object of the invention is to provide in a burner of the type described, a manifold in which are grouped all the necessary valves, thermostats, or other instruments necessary to the accomplishment of the objects above set forth and in which are formed inlet and outlet chambers for the low-pressure oil used for heating purposes, and a valve chamber for the high-pressure oil to be fed to the feed conduit of the oil nozzle.

A further object of the invention is to provide

an adapter ring which is arranged to be inserted between the fan housing and the air tube of an oil burner and which carries the aforesaid manifold, the arrangement enabling an ordinary burner to be converted easily and conveniently into one having the oil-preheating provisions desirable to render the burner capable of handling heavy fuel oils.

These and other objects will best be understood as the detailed description proceeds and they will be pointed out in the appended claims.

The invention will be disclosed with reference to the accompanying drawings, in which:

Figs. 1 and 2 are small-scale, top-plan and side elevational views, respectively, of a burner embodying the invention;

Fig. 3 is a fragmentary cross sectional view, taken on the line 3—3 of Fig. 1 and drawn to a larger scale;

Figs. 4 and 5 are sectional plan views taken on the lines 4—4 and 5—5, respectively, of Fig. 3;

Fig. 6 is a sectional elevational view, taken on the line 6—6 of Fig. 1 and drawn to a larger scale;

Figs. 7, 8 and 9 are sectional views taken on the lines 7—7, 8—8, and 9—9, respectively, of Fig. 6;

Figs. 10 and 11 are sectional views taken on the lines 10—10 and 11—11, respectively, of Fig. 3;

Fig. 12 is a fragmentary sectional plan view taken on the line 12—12 of Fig. 6; and

Fig. 13 is a small-scale elevational view showing the burner mounted to fire a boiler.

Referring to these drawings, and first to Figs. 1 and 2 thereof, the burner includes a suitable fan, the housing of which is marked 16, for supplying air to the burner; a suitable pump 17 for supplying oil to the burner; a motor 18 for driving both fan and pump; and a cylindrical air tube 19 through which air is conducted to the point of combustion. Within this tube (Fig. 6) is a suitable nozzle 20 for emitting oil in finely-divided form to be mixed with the air. The nozzle, in this particular case, is of the pressure atomizing type. The air tube may have any suitable outlet nozzle or other means for directing the air to the oil spray, such for example as the nozzle 22 (Figs. 1 and 2). The assembly described is usually supported (see Fig. 2) by several legs, such as 21, and the forward end of the air tube 19 is inserted through a wall w of the heating unit so as to communicate with the combustion chamber c thereof in the usual or any suitable manner.

The elements, above described, are found in the association described in many burners of the prior art. The burner described thus merely constitutes the setting or background for the present invention, which relates primarily to apparatus for preheating the oil and bringing it up to a predetermined temperature before flow of the oil to the atomizer nozzle 20 is permitted.

In carrying out the invention, an adapter ring 23 (Fig. 2) is interposed between the outlet end of fan housing 16 and the inlet end of air tube 19, and is suitably secured to the housing as by cap screws 24. The tube 19 is also suitably fixed to the adapter as by screws 26, which clamp the end of the tube against a circular flange 25 (Fig. 6) on the adapter. This adapter supports on its upper side a manifold 27 which is fixed by cap screws 28 (Fig. 3) to the adapter and which is provided with various chambers and passages for the oil. The manifold, in turn, is connected as shown in Fig. 6 to supply oil to the nozzle 20 and to circulate oil through jackets which encompass the oil supply passage, all as will be more particularly described hereinafter.

The manifold 27 will first be described. Referring to Figs. 1 and 3, this manifold is provided at a point intermediate its ends with a vertically-disposed, cylindrical chamber 30 and on opposite sides of this chamber with chambers 31 and 32. The chambers 31 and 32 are inlet and outlet chambers, respectively, for the low-pressure oil used for heating the oil-supply passage of nozzle 20. The chamber 30 is for the high-pressure oil used to supply said passage and nozzle. Adjacent the inlet chamber 31 at one end of the manifold is a cylindrical chamber 33 for a pressure-regulating and by-pass valve. Partially surrounding the chamber 33 is an inlet jacket composed of two connecting portions 34 and 35 (Fig. 11). The pump 17 has a discharge pipe 36 (Fig. 1) and this pipe is connected to the portion 34 (Figs. 10 and 11). The portion 35 is connected by a port 37 (Figs. 3 and 11) to chamber 33 near the base thereof. An L-shaped outlet passage 38 (Fig. 10) is provided for the high-pressure oil which passes the pressure-regulating valve to be described. This passage 38 extends horizontally rearward below the chamber 33 and thence upwardly toward the portion 34 of the inlet jacket, such portion being of less height than the portion 35 in order to accommodate the upwardly extending part of passage 38. At its upper end passage 38 communicates with one end of a passage 39 (Figs. 5 and 10) which extends in back of inlet chamber 31 (Fig. 5) and at its other end is connected by a port 40 with the chamber 30. The upper end of valve chamber 33 is connected by a port 41 (Fig. 3) to an arcuate recess 42 which forms an upward extension of inlet chamber 31 near one end thereof.

The oil supply connections between the manifold 27 and the nozzle 20, together with the connections between the manifold and the heating jackets will next be described. Below and axially-aligned with chamber 30 and separated therefrom by a wall 43 (Figs. 3 and 6) is a cylindrical recess 44. A casting 45 having a flange 46 secured by cap screws 47 to the lower wall of the manifold, has a cylindrical portion 48 which closely fits the recess 44. This casting has three L-shaped passages 49, 50, and 51 therethrough. The two outer passages 49 and 51 terminate at their upper ends with lateral ports 52 and 53, respectively, which communicate with passages 54 and 55, leading to the inlet and outlet cham-

bers 31 and 32, respectively. The central passage 50 is connected at its upper end to a short pipe 56 having on its upper end a seat for a valve 57. The pipe 56 extends through wall 43 and is screw-threaded into the upper end of the cylindrical part 48 of casting 45. As shown in Fig. 6, the casting 45 is fixed, as by cap screws 58, to a casting 59. The casting 59 has three passages 60, 61 and 62 (Fig. 8), which respectively communicate as shown in Fig. 9, with passages 49, 50, and 51. These passages 60, 61, and 62 have their lower terminal ends disposed in a common horizontal plane (Fig. 12) which passes through the axis of the cylindrical lower end 63 of casting 58. The end 63 is bored out to receive one end of a pipe 64 and is counterbored to receive the corresponding end of a larger pipe 65 which is disposed coaxially of and encompasses pipe 64. The left hand end of pipe 64 extends beyond the corresponding end of pipe 65 and communicates with the passage 61. The passages 60 and 62 open into the end face of the counterbore which receives pipe 65 and they communicate with the latter at diametrically opposite points. The annular space between the pipes 64 and 65 is partitioned by two members 66 (Fig. 7) which are suitably fixed to the outer wall of pipe 64, as by welding, and which extend longitudinally of the pipe, one along the top and one along the bottom thereof. These members divide the aforesaid annular space into two parts or jackets 67 and 68, with which the passages 60 and 62, respectively, communicate. The members 66 (Figs. 12 and 6) extend from the left hand end of pipe 65 to a position adjacent but spaced from the right hand end of this pipe. The right hand end of both pipes 64 and 65 are threaded into a block 69 which carries the atomizing nozzle 20 and has a passage 70 interconnecting the nozzle and the right hand end of pipe 64. There are upper and lower spaces 71 between the right hand ends of members 66 and block 69 and these spaces enable oil which is fed into the left hand end of one passage, as 61, and through such passage, to enter into the right hand end of the other passage, as 68, and return to the left hand end of such passage. The left hand end of pipe 64 has a press fit in its recess in the end 63 of casting 58. The left hand end of pipe 65 closely fits in the counterbore in such end 63 and the pipe 65 is fixed to end 63 in any suitable way, as by welding.

The structure described provides an oil feed passage which extends from chamber 30 to the nozzle 20 without interruption. This feed passage may be traced as follows: from chamber 30 through pipe 56, passages 50 and 61, pipe 64 and passage 70 to nozzle 20. The structure also provides a continuous heating passage from the chamber 31 of the manifold 27 extending along-side the feed passage to a point near the nozzle end thereof and then returning along the opposite side of the feed passage to the chamber 32 of the manifold. This heating passage may be traced as follows: from chamber 31 through passage 54, port 52, passages 49 and 60, jacket 61, spaces 71, jacket 68, passages 62 and 51, port 53 and passage 55 to chamber 32.

The pressure-regulating and by-pass valve will next be described with reference to Fig. 3. Threaded into the bottom wall of chamber 33 and upstanding therefrom is a hollow barrel 72 which communicates at its lower end with the outlet passage 38 for high-pressure oil. The barrel is counterbored to slidably receive a plunger 73, having depending therefrom a valve 74 to control

communication between the interior of the barrel and outlet passage 38. Ports 75 in the side wall of barrel 72 above the seat for valve 74, enable oil from chamber 33 to enter the hollow interior of the barrel at a location below the plunger 73. A spring 76 tends to raise this plunger and open valve 74. The plunger, however, has fixed thereto a second valve 77 which projects upwardly through the top end of the barrel and engages the lower face of a piston 78, closing an opening 79 which extends through the bottom wall of the piston. The piston is slidably mounted in the upper part of chamber 33 and is forced downwardly by a spring 80, mounted between the piston and a suitable seat provided within a cap 81 which is threaded into and closes the otherwise open upper end of chamber 33. The tension of this spring is adjustable in the usual or any suitable manner. The spring 80 is much stronger than spring 76 and thus holds valve 74 closed until a pressure has been built up in chamber 33 beneath the piston of sufficient degree to raise the latter, say for example 150 pounds per square inch. When the piston 78 commences to rise, valves 74 and 77 and plunger 73 will rise with it because of the lifting effect of spring 76. Valve 74 will thus open and allow oil to flow from chamber 33 to passage 38. The valve 77 does not, however, immediately open. When the plunger 73 rises far enough to engage the upper wall of barrel 72, the upward movement of both valves will be stopped. Thereafter, as the piston continues to rise, it will draw away from the valve 77, opening the passage 79. Then oil from the lower part of chamber 33 will pass through the piston into the upper part of the chamber and thence pass through port 41 and recess 42 into inlet chamber 31. This oil which is "bypassed" and at low unit pressure is used for heating purposes in the circulatory heating passages above described.

Provision is made, whereby the pressure of that body of oil contained in passages 38 and 39, port 40 and chamber 30 will be automatically reduced to that existing in chamber 33, whenever valve 74 is closed. An axial passage 82 (Fig. 3) in this valve extends upwardly from its lower end and communicates by means of side ports 83 with the interior of barrel 72 and thus with chamber 33. A check valve 83', preferably spring-pressed as shown, is provided in the passage 82 between the ends thereof. This valve opens whenever the pressure on the lower side of the valve exceeds that in chamber 33, allowing back flow of oil into this chamber until the pressures on opposite sides of valve 74 are equalized. The spring associated with valve 83' does not exert any substantial pressure on the valve and is there merely to insure that the valve is held to its seat more positively than it would be if gravity alone were relied on for the purpose. Because of the provision described, whenever the oil pump stops, the pressure in chamber 30 and in the port and passages communicating therewith is automatically reduced usually to zero and in any case to whatever pressure exists in chamber 33.

A pressure gauge 84 may be connected to the inlet passage 35 as shown.

The chamber 32 has two outlets. One outlet is by way of a pipe 85 (see Fig. 4) which pipe extends, as shown in Figs. 1 and 2, to the inlet end of a suitable oil heater, such as the electric heater indicated at 86. A spring-loaded check valve 87 is interposed in pipe 85. This valve opens to permit flow toward and into the heater 86 when

a small pressure, say from 8 to 10 pounds per square inch, has been built up in the chambers 31 and 32 and the oil circulation passages connected therewith.

5 The heater 86 has its own thermostatic switch, designated 88, for controlling the supply of current thereto and it may also be additionally controlled by other means not herein shown.

The heater has an oil inlet 89 adjacent pipe 85 (see Fig. 2). The outlet end of heater 86 communicates with a filter of any suitable form within a casing 90, preferably formed as a part of the casing of the heater, whereby the oil within the filter is kept warm. Oil from the filter passes by way of a pipe 91 to the suction side of pump 17. Thus, the pump may draw oil from either pipe 85 or the inlet 89, sucking it through the heater and filter and then forcing it into the chamber 33 of the pressure-regulating and bypass valve. Until valve 57 opens, the only outlet for the oil is into chamber 31, and thence through the circulation passages associated with the nozzle supply passage and thence back to chamber 32. Initially, oil leaves this chamber only by way of pipe 85 and then passes back to the inlet side of the oil heater. Therefore, a relatively small volume of oil only is necessary for the circulation through the heater and along the nozzle supply passages for heating purposes. A quick raising of the oil temperature can thus be secured.

The temperature of the oil may be indicated on a suitable thermometer 92 communicating with chamber 32.

35 The other outlet for chamber 32 is by way of a pipe 93 (Fig. 3) which is adapted, as shown in Fig. 13, to return oil to the oil supply tank 128. Communication between the chamber 32 and return pipe 93 is controlled by a valve which opens in response to rise in temperature of the oil in the chamber, opening the valve only when such temperature reaches a predetermined degree. Initially then, this valve is closed. As herein shown, a hollow barrel 94 is fixed to and stands from the lower wall of chamber 32. The lower end of this barrel is in constant communication with pipe 93. The barrel has side ports 95 enabling communication between the interior of the barrel and chamber 32. A sleeve valve 96 slides in this barrel and has ports 97 adapted to register with ports 95 when the oil temperature reaches the predetermined degree. A spring 98 tends to raise the valve and keep ports 95 closed. Fixed by a cap screw 99 to a cap 100 threaded into the top wall of chamber 32 is a thermostatic bellows 101, to the lower end of which the flange 96' of the valve 96 is fixed. As the temperature of the oil in chamber 32 rises, the bellows 101 extends and forces the valve 96 downwardly, causing ports 95 and 97 to communicate when the desired oil temperature is attained and thus allowing oil to flow back to the supply tank. Any suitable provisions may be made for adjusting the temperature at which valve 96 will open. As shown herein, the spring 98 is interposed between the upper end of the barrel and the lowermost of two washers 98' on the stem of the valve below flange 96'. By varying the number or the thickness of these washers or by both, the pressure which opposes the bellows 101 and thus the temperature at which valve 96 will open can be varied as desired. Any other suitable means for controlling valve 96 in response to oil temperature may be used, as desired.

The valve 57, which controls the flow of high-pressure oil from chamber 30 to the nozzle 20, is automatically opened when the oil has attained the desired predetermined temperature. For example, the valve may be operated electromagnetically under the control of a thermostat switch designated 103, having a thermal element 104 extending into chamber 32 (Figs. 4 and 5). This switch is arranged to close when the oil in chamber 32 reaches the desired predetermined temperature and the closing of the switch is arranged to energize a solenoid 105 which raises valve 57. The solenoid is mounted on a body 106 having a flange 107, which is secured by cap screws 108 to the top of manifold 27. Preferably, a baffle, such as 104' (Fig. 5) is provided in order to deflect the oil which enters chamber 32 through port 55 toward the thermostat element 104.

The high-pressure oil chamber 30 is preferably provided with a screen 109 which is held between the flange 107 and the bottom wall of chamber 30, the ends of the screen fitting into recesses, one in said flange and one in said wall.

The various pipe plugs, such as 110, shown in the manifold 27, are used to plug the holes, left by the supports for the cores, used during the casting of the manifold.

Referring to Fig. 13, the burner is shown as used for firing any suitable heating unit, say for example a boiler 111. This boiler has an indirect heater 112 through which water from the boiler circulates by means of pipes 113 and 114. The water is arranged to heat the oil which enters the heater by a pipe 115, leading from the oil supply tank 128 and leaves by a pipe 116, which extends to the above described inlet 89 of the electric heater 86. The pipe 115 may have a foot valve 129 thereon.

In accordance with usual practice, the air tube 19 (Figs. 1 and 2) has an opening in the upper portion thereof, and such opening is normally closed by a cover 117 held in place by screws 118. By removing this cover and the plate, one may remove the oil supply and heating conductors together with the nozzle and the usual nozzle support, such as 119 (Fig. 6), and the ignition electrodes, such as 120, which are supported by insulators 121 from the member 119. The cap screw 119 which holds support 119 in place in tube 19, is first removed. Then by removing the cap screws 58, one may separate the two castings 45 and 59, whereupon after the casting 59 has been turned enough to clear casting 45, the casting 59 and the attached pipes 64 and 65 and nozzle 20 may be drawn rearwardly and lifted upwardly through the opening in the air tube.

The casting 45 extends through a slot 124 (Fig. 6) in the adapter ring 23. This slot is open at one end. To prevent air from passing outwardly through this slot, a plate 125 is laid on the top wall of the adapter 23 to overlie the open portion of slot 124 and to fit closely against the front and sides of that portion of the casting which lies in the slot. This plate is fixed to the adapter by screws 126. This plate may have an upturned flange 127 to abut the cover 117 and exclude outflow of air from the tube 19 above plate 125.

The burner structure described may be provided with any suitable electrical controls, which may be contained for the most part in a control box 122. One example of a control system suitable for this burner is disclosed in our copend.

ing application Serial No. 314,102, filed January 16, 1940.

The operation of the burner will next be described. The burner will be started up automatically, on a demand for heat, by suitable controls such for example as those disclosed in the above identified application, which controls set in operation the motor 18, fan 16 and pump 17 and usually also turn on the electric heater 86 and the ignition means. Flow of oil to the nozzle is, however, prevented by valve 57 unless and until the oil has been heated to the desired predetermined temperature. This temperature may, for example, be assumed to be from 140° to 150° Fahr. for No. 5 fuel oil. Assuming that the oil temperature is low, the thermostat valve 96 will be closed with the result that the oil will be forced by pump 17 to circulate through the short path described. The pump will put the oil under a small pressure, sufficient to open the spring-loaded check valve 87. Oil will be forced into the manifold 27, out through jacket 67 to a position closely adjacent nozzle 20, back through jacket 68 to the manifold, and thence by way of pipe 85 through valve 87' into the inlet side of the electric heater 86, from which oil is delivered to the suction side of the pump. It is to be noted that no oil will pass through the indirect heater 112 and this is a most important feature. The normal function of heater 112 is to yield heat to the oil which passes therethrough by a heat exchange between the water in the boiler 111 and the oil. But, if this water is cold and the oil which has been heated by heater 86 is allowed to pass through heater 112, the oil will be cooled. The normal heat exchange will be reversed and the oil will yield its heat to the water in the boiler and unless and until the water is brought up to the desired oil temperature, the burner cannot operate. Thus, the initial use of the indirect heater would delay the starting up of the burner.

The quickest way to heat the water in boiler 111 is by direct firing of it by the oil burner. This occurs as soon as the oil has been heated to the proper degree, because the thermostat switch will close and cause energization of solenoid 105, thereby raising valve 57 and allowing heated oil to flow through the passages, which form the nozzle feed pipe, into nozzle 20. At or about the same time, but preferably somewhat later, the thermostat 101 will open valve 96 and allow circulation of oil through the long circuit which includes the supply tank and the indirect heater 112. The thermostat 101 is usually set to open valve 96 only after the oil has risen to a temperature somewhat above—say 5 to 10 degrees—that at which valve 57 opens.

In starting up the burner from a cold condition with the water in the boiler also cold, the burner may not at first continue in operation very long after it has been started. After the nozzle valve 57 has opened and oil is supplied to and ignited at the nozzle, the water in the boiler begins to warm up. Obviously, the oil consumed at the nozzle must be drawn from tank 128 through the indirect heater 112. Consequently, the oil temperature in the manifold will be lowered and eventually lowered to a point where the valve 57 will close and stop flow of oil to the nozzle. The fire goes out but the pump continues in operation, forcing oil in the short path through the electric heater, whereby the oil will soon be heated to the point where valve 57 will again open and allow oil to be fed to and ignited.

at the nozzle, thereby again firing the boiler. Usually, the burner will run four or five minutes on the first start and then stop. Two or three starts usually suffice to secure operation which is continuous. Thereafter, the temperature of the oil in the manifold will rise to a point where valve 96 will open, whereupon oil will then circulate through the longer circuit which includes the tank 128 and the indirect heater 112.

When the boiler water is not cold (and it is usual to maintain it by thermostatic control at same predetermined temperature above that at which valve 57 opens), then the repeated starting and stopping of the burner, above described, will not usually occur.

The provision of the manifold 21, in which are mounted all of the various valves 57, 74, 77 and 96, thermostats 101 and 104, the pressure gauge 84, and thermometer 92, is an important feature of the invention. Not only are all these necessary instruments grouped together in one place and made conveniently accessible but they are kept warm by the body of hot oil contained in the chambers of the manifold and thus in condition to be instantly responsive in the performance of their intended functions. The manifold together with the adapter ring 23 enables a standard burner to be easily converted into one having the oil-preheating provisions. The adapter ring 23 which carries the manifold, is simply interposed between the outlet of the fan housing 16 and the inlet end of the air tube 19 and all that remains to do is to connect three pipes 36, 85 and 93 thereto.

The temperature-controlled valve 57 is purposely located away from the nozzle 20 to keep it away from the intense heat which might interfere with its proper functioning and also to make it accessible. With the remote location of this valve, the provision of the jackets 67 and 68 and their connecting passages enable the warming up of that body of oil which is trapped between the valve 57 and the nozzle 20. The oil feed conduit has uninterrupted heating passages extending between such valve and nozzle so that, when flow of oil to the nozzle eventually occurs, there will be no possibility of the emission of any slug of cold oil. All the oil will be brought up to temperature by the circulatory heating system described. Even the oil contained in the nozzle 20 and in passage 70 will be heated by conduction from the pipes 64 and 65.

The invention thus provides an improved means for preheating the fuel in an oil burner, which insures that the oil may be quickly raised to the desired temperature and maintained within close limits at such temperature. No oil can pass to the nozzle until it has attained the selected temperature. Unless the oil is at the right temperature and also under the proper pressure, it cannot pass to the nozzle.

What we claim is:

1. In an oil burner, having an oil pump, an oil-atomizing nozzle, and a feed pipe for supplying oil thereto, said pipe having heating jackets extending from end to end thereof and disposed one on each side thereof, said jackets being interconnected near the nozzle end thereof, an oil heating means, a supply pipe leading to the inlet end of said means, a pipe connecting the outlet end of said means to the inlet end of said pump, a conduit connecting the outlet end of said pump to said feed pipe, first and second valves interposed in series relation in the order named in the last-named conduit, the first valve opening when

the pumped oil attains a predetermined pressure, the second valve opening only when the oil attains a predetermined temperature, a by-pass for diverting excess oil supplied to the first valve, 5 a conduit connecting said by-pass to the inlet end of one of said jackets, and a conduit connecting the outlet end of the other of said jackets to the inlet end of said heating means.

2. In an oil burner, having an oil pump, an oil-atomizing nozzle, and a feed pipe for supplying oil thereto, said pipe having heating jackets extending from end to end thereof and disposed one on each side thereof, said jackets being interconnected near the nozzle end thereof, an oil heating means, a supply pipe leading to the inlet end of said means, a pipe connecting the outlet end of said means to the inlet end of said pump, a conduit connecting the outlet end of said pump to said feed pipe, first and second valves interposed in series relation in the order named in the last-named conduit, the first valve opening only when the pumped oil attains a predetermined pressure, the second valve opening only when the oil attains a predetermined temperature, a by-pass for diverting excess oil supplied to the first valve, a conduit connecting said by-pass to the inlet end of one of said jackets, a conduit connecting the outlet end of the other of said jackets to the inlet end of said heating means, and a check valve controlled by-pass for enabling back flow around the first valve to equalize the pressure on opposite sides of said valve.

3. In an oil burner, wherein air for combustion is supplied by a fan through a tube and oil is supplied through a feed pipe located within said tube to an oil-atomizing nozzle, a manifold mounted on said tube adjacent the fan and having therein a chamber for oil to be fed to said pipe and nozzle and also having therein inlet and outlet chambers, a pressure-regulating and by-pass valve mounted in said manifold and having its inlet connected to said pump and its high pressure outlet connected to the first-named chamber and its by-pass outlet connected to said inlet chamber, the first-named chamber having an outlet connected to said feed pipe, a valve controlling said outlet, said feed pipe having heating jackets the inlet end of one of which is connected to said inlet chamber and the outlet end of the other of which is connected to said outlet chamber, the outlet end of the first jacket being connected at a point closely adjacent the nozzle to the inlet end of the second jacket, a heating means for oil, a connection between said outlet chamber and the inlet of said heating means, a connection between the outlet of said heating means and said pump, and a thermostat located in said outlet chamber and operable to open said valve when the oil in said chamber attains a predetermined temperature and to close said valve when such oil is below said temperature.

4. In an oil burner, an oil-atomizing nozzle, means for heating the oil to be supplied to said nozzle, a conduit extending from the heating means to said nozzle, a valve in said conduit located a substantial distance from the nozzle and opening only when said oil has attained a predetermined temperature, a heating jacket for said conduit extending without interruption from said valve to said nozzle, and means for circulating oil heated by the first named means through said jacket to warm the body of oil trapped between said valve and nozzle.

5. Fuel heating means for an oil burner used

for firing heating apparatus and having, a first oil-heating means dependent for effectiveness on operation of the heating apparatus, a second oil-heating means effective independently of the operation of said apparatus and burner, a pump, and conduit means interconnecting said pump and the first and second oil-heating means in series relation and providing a relatively-long closed-loop path in which oil may be circulated by said pump; conduit means cooperating with part of the first-named conduit means to provide a relatively-short closed-loop path for the circulation of oil by said pump and including in series relation said pump and the second only of said heating means, and means responsive to the temperature of the oil for causing the pumped oil to flow through said short path and be excluded from the long path until the oil has been heated to a predetermined temperature by said second heating means and for then causing the pumped oil to flow through said long path and both heating means.

6. Fuel heating means for an oil burner used for firing heating apparatus and having an oil supply conduit for said burner, a first oil-heating means dependent for effectiveness on operation of the heating apparatus, a second oil-heating means effective independently of the operation of said apparatus and burner, a heating conduit located in heat exchange relation with said supply pipe, a pump, and conduit means interconnecting said pump and heating conduit and the first and second oil-heating means in series relation and providing a relatively-long closed-loop path in which oil may be circulated by said pump; a valve in said conduit means located between the outlet of said heating conduit and the inlet of the first heating means, means responsive to the temperature of the oil for opening said valve only when the oil is at or above a predetermined temperature and closing said valve when the oil is below said temperature, a by-pass extending between two points in said conduit means, one of said points located between the outlet of the first heating means and the inlet of the second heating means and the other of said points located between said valve and the outlet end of the heating conduit, a check valve in said by-pass opening when said first valve is closed and when the pumped oil exceeds a predetermined pressure to enable direct flow from the heating conduit to the second heating means to the exclusion of the first heating means.

7. Fuel heating means for an oil burner used for firing heating apparatus and having, a first oil-heating means dependent for effectiveness on operation of the heating apparatus, a second oil-heating means effective independently of the operation of said apparatus and burner, an oil supply pipe for said burner, a heating conduit located in heat exchange relation with said pipe, a pump, an oil supply tank; an oil conduit connecting said tank to the inlet of said heating conduit and having interposed therein in series relation and in the order named said first heating means, said second heating means, and said pump; a first return conduit connecting the outlet of said heating conduit to the inlet of the second heating means, a check valve in said return conduit, a second return conduit extending from the outlet of said heating conduit to said tank, a valve for closing the second return conduit, whereby the oil circulated by the pump will pass through the second only of said heating means, and means responsive to the temperature of the

oil in said heating conduit for opening said last-named valve when such oil has been heated to a predetermined temperature, whereby the oil circulated by the pump will then pass through both heating means and said tank.

8. Fuel heating means for an oil burner used for firing heating apparatus and having, a first oil-heating means dependent for effectiveness on operation of the heating apparatus, a second oil-heating means effective independently of the operation of said apparatus and burner, an oil supply tank, a pump, a suction conduit connecting the tank and pump and having interposed therein the first and second heating means, a discharge pipe for said pump, a pressure regulating valve and a by-pass valve, each said valve having its inlet connected to said discharge pipe, a feed pipe connected at one end to the outlet of the pressure regulating valve and an atomizing nozzle on the other end of the feed pipe; a heating conduit mounted in heat exchanging relation with said feed pipe and having its inlet connected to the outlet of said by-pass valve, a third valve located in said feed pipe between the nozzle and the pressure regulating valve, means for opening the third valve only when the oil has been heated up to a predetermined temperature, a first return conduit connecting the outlet of the heating conduit to the inlet of said second heating means, a check valve in said return conduit, a second return conduit connecting the outlet of the heating conduit to said tank, a valve for initially closing the second return conduit, whereby the pump will circulate oil through the heating conduit and the second heating means only; and means responsive to the temperature of the oil in said heating conduit for opening the last-named valve, when such oil has been heated to a predetermined temperature, whereby the pump then circulates oil through the heating conduit and both heating means and said tank.

9. In an oil burner, having a pump, an atomizing nozzle and an oil feed conduit interconnecting the outlet of the pump and said nozzle, means for heating the oil supplied to said pump, two valves interposed in said conduit at a substantial distance from said nozzle, one of said valves opening only when the pumped oil attains a predetermined pressure, the other of said valves opening only when the oil attains a predetermined temperature, a heating conduit mounted in heat exchange relation with that portion of the feed conduit located between said nozzle and the nearest one of said valves, a conduit connecting said feed conduit at a point between the pump and the valve nearest thereto to the inlet of said heating conduit, a conduit connecting the outlet of the heating conduit to the inlet of the oil heating means, and a conduit connecting the outlet of the oil heating means to the inlet of said pump.

10. In an oil burner, having a pump, an atomizing nozzle and an oil feed conduit interconnecting the outlet of the pump and said nozzle, means for heating the oil supplied to said pump, a valve responsive to pressure of the pumped oil and a valve responsive to the temperature of the oil, said valves interposed in the feed conduit in series relation with the first-named valve nearest to the pump and the second-named valve nearest to the nozzle but both valves being spaced a substantial distance from the nozzle, both valves being initially closed to prevent flow of oil to the nozzle, a heating conduit mounted in heat exchange relation with that portion of the feed conduit which lies between the temperature responsive

valve and said nozzle, a conduit connecting the inlet of the heating conduit to the inlet of the pressure responsive valve, a conduit connecting the outlet of the heating conduit to the inlet of the oil heating means, and a valve interposed in

5 said last-named conduit and opening in response to pressure of the pumped oil, the inlet of said heating means being connected to the outlet of the heating conduit and the outlet of said heating means being connected to the inlet of said pump.
